MANIFOLDING REGISTER

William G. Borchers, Hoboken, N. J., assignor to
 Autographic Register Company, Hoboken, N. J.,
 a corporation of New Jersey

Application November 24, 1936, Serial No. 112,511

5 Claims. (Cl. 282—16)

This invention relates to manifolding sales registers, such as are usually employed in stores, for recording sales by making suitable entries on forms printed on one or more strips which are stored, preferably in a zig-zag pile, in the storage compartment of the machine.

An object of the invention is: to provide a machine of the character described in which the top or cover plates, which normally close the tops 10 of the several compartments, may be swung upward to expose and permit unobstructed access to the interiors thereof, the cover plates being so organized that, when they are closed, the locking of one of them will prevent all of them 15 from being opened or tampered with.

Heretofore, in this type of machine, locking means were provided only for the compartment in which the filled-in forms to be preserved for official records of the sales-transactions are kept 20 intact, while easily-accessible spring catches or similar devices were, and still are, in common use for retaining the writing platen and its superposed margin frame in their operative positions. In other words, anyone could, without 25 having to use a key, open the rear portion of the machine and thus have access to the storage compartment for the form-pile, and also to the entire feeding mechanism including the starting device, feed-rolls and other connected ap- 30 purtenances.

The present invention aims to obviate and remedy that fault by making the cover organization so that an interlocking connection between the several covers will be established in such a manner 35 that they must be closed in a particular sequence before the last or final closure may be locked by a key, and the interior of the machine cannot be tampered with.

Another object of the invention is: to provide 40 means for checking or preventing any one cover from being closed before its predecessor is in its proper position, this means being particularly applied to the cover of the record compartment, which cover carries the lock whereby the entire 45 machine is finally securely closed.

Still another object of the invention provides 50 means for assuring the feed-rollers being in proper strip-gripping condition when the lock-cover is closed, the latter being directly responsible for automatically allowing the feed rollers to drop 55 into contact with the manually operable feed disks for the form strips, even if the rollers should have been inadvertently left in non-gripping positions, improved means being also provided for leaving the operating crank after each

feed operation ready for the next one without requiring any releasing action by the operator.

Other features of the invention will hereinafter appear.

Referring to the drawings:

Figure 1 is a plan of a machine embodying my invention.

Fig. 2 is a longitudinal vertical section, substantially on line 2—2 of Fig. 1.

Fig. 3 is a horizontal section, on line 3—3 of 10 Fig. 2.

Fig. 4 is a section similar to Fig. 2, but showing the cover-plates in opened and transitory positions.

Fig. 5 is a fragmentary side elevation of the 15 machine showing the device whereby the feed-crank is stopped at the end of each revolution and then automatically released.

Fig. 6 is a horizontal section on line 6—6 of Fig. 5.

Figs. 7 and 8 are sections similar to Fig. 6, 20 illustrating progressive positions of the crank and its stopping device.

Referring first to Fig. 2, the machine is shown in normally operative condition, and it comprises 25 a box-like casing consisting of a bottom plate 10, front end wall 11, rear end wall 12, and side walls 13 and 14, respectively. The strip-feeding mechanism, indicated in a general way by M, divides the interior of the casing into two compartments, viz: a rear compartment 15 which serves as storage room for a zig-zag pile 16 of 30 form-strips 17, and a front compartment 18 for receiving the official copies of the filled-in sales recording forms which are to be preserved. In 35 order to locate the pile 16 properly within its compartment 15, there are provided a pair of L-shaped partitions or gauge plates 19, secured to the bottom plate and extending upwardly therefrom to have their upper edges 19' serve 40 as supports for a platen 20 which may be made of thin metal and still be stiff enough for its purpose, by virtue of its side margins being supported by the partitions 19. At its front edge the platen 20 is hinged by pins 21a to the front ends 45 of a pair of links 21 whose rear ends are firmly secured to a rocker-rod 22 journaled in vertical bearing-plates 23, 24 forming parts of the casing structure, the rear free end of the platen being, therefore, movable in a vertical and rearwardly directed arc. It will be understood that, 50 by virtue of this articulation, the platen 20 is fully supported on both of side-margins, as well as at its front end, while its rear end is stiffened by an integral curl 20a disposed between a pair 55

of downwardly-bent lips 25 which rotatably support a guide-roller 26 over which the form-strips 17 are passing onto the platen 20.

It should be noted that, while the strips are represented by one dot-and-dash line 17 only, several of such strips may be employed in assembled form, in which instance carbon sheets would naturally be interleaved with the form-strips to produce copies which are duplicates of the inscriptions written upon the top form-strip when resting upon the platen 20. The interleaved carbons may be of any suitable size or form, and may be attached to hooks 20b lanced from the platen and bent-up as usual, and as is clearly shown in the drawings.

Disposed above the platen 20, is the margin-frame 27 having the writing opening 28 and provided at its rear end with hinge plates 29 whose cooperative leaves 30 are secured to the rear wall 12 of the casing. Near its front end the margin-frame 27 is adapted to rest normally on a pair of pins 31 projecting upwardly from the platen 20, and it also carries a housing 32 which is adapted to move in a vertical-plane arc 27c intersecting the platen arc 20c in the normal condition of the machine, entirely encloses the pressure roller 33 which forms an element of the strip-feeding mechanism M above referred to. The housing 32 also covers the superstructures 23a, 24a extending upwardly from the plates 23, 24, respectively, and being slotted vertically to receive, for vertical sliding movement therein, the ends of the roller shaft 34.

The fact that the housing 32 forms an integral part of the margin frame 27 is an important feature of the present invention, because, when said frame is swung upwardly on its rear end hinge connection 29, 30, as for instance to the position shown in full lines in Fig. 4, the entire pressure roller and its support will become exposed and accessible for easy assembling or dismounting of the several parts. Furthermore, inasmuch as the margin frame 27 is then entirely out of the way, the insertion of the form strips and their introduction into the bite between the pressure roller and its underposed feeding disks can be very readily accomplished. When the margin frame 27 has been raised to a position substantially as shown at 27A, the platen 20 may be also raised or swung upwardly, past the position 20A and to the limit shown at 20B, thus leaving the entire rear pile-compartment free to unobstructed access, for the purpose of removing or inserting a strip-pile. According to my present invention, the platen is hinged at its forward end, instead of its rear end, the result being: that when the platen is swung upward, the guide roller 26 is at a considerable altitude above the storage compartment and free to access from either side (upper or lower) of the platen, and consequently renders the threading-in of the form strips around the roller an easy operation. Furthermore, the hooks 20b are in a position where the carbon sheets can readily be interleaved with the work-sheets and hung onto the hooks in suspended or hanging-down position, in contradistinction to the old-way results attained when the platen is hinged at its rear end and the difficult and unhandy conditions inherent thereto are met.

When the platen 20 is in normal writing position, its front edge must necessarily be close to the bite of the feed-rollers to give proper support to the form strips resting on the platen. Referring to Fig. 2 it will be seen that the front

edges of the platen 20 and the links 21 project partly over the feed mechanism M, which latter comprises a crank shaft 35 journaled in the casing plates 23, 24 and provided at the outside of the casing with a manually-operable 5 crank 36.

This shaft carries the usual feed-starting device 37 and the feeding-disks 38 with which the pressure rollers 33 cooperate in feeding one form-length of strips for each full rotation of 10 the shaft 35, the operation being well-known in the art.

Again referring to the overlap of the front-portion of the platen over the feed-mechanism, more particularly the disks 38 thereof, it is evident that it will be impossible to lift the shaft 35 together with its disks, out of its place in the casing, or to replace it, unless provision is made for removing the overlapping portion of the platen, and also to provide a passage through 20 the stationary deflector plate 40, the latter being cut away at three places 40a, to clear the path for the starter 37 and disks 38 when the shaft 35 is lifted out of its place. The invention therefore comprises the pivot-linkage above de- 25 scribed and capable of assuming a clearance-position, such as indicated at 20C in Fig. 4, in which the hinge-links 21 have been swung upward around the center of the rod 22 sufficiently to afford free vertical passage of the feed-shaft 30 35 out of or into its proper position in the casing-plates 23, 24 for which operation it is obvious that the pressure roller 33 must be first removed.

In recapitulation, the hinge-pins 21a can 35 move to several positions relative to the cas- ing, viz. (1) the normal position shown in Fig. 2, where they are controlled and fixed by virtue of the platen resting with its marginal portions on the partitions 19; (2) that shown by platen-positions 20A and 20B, in which case the platen 40 can be swung on an arc delineated by the line 20a' to leave free access to the storage compartment 15, the front edge of the platen then resting on the peripheries of the feed-disks 37; (3) 45 that incidental to the platen-position 20C, the hinge pins having been swung from their extreme left (as per 20B) to the extreme right (as per 20C), to permit free access to the feed mech- anism M.

According to the present invention, there is provided for the form-strips, as they are fed forwardly by the cooperating feed disks 38 and pressure roller 33, a thin deflector-plate 40 ex- 55 tending across the machine and supported on a cross-bar 41 which has at its ends lips 41a se- cured to the plates 23, 24 respectively. This deflector plate 40 is slightly bent as shown, so as to bring its free edge closely adjacent to the bite of the feed-disks and roller 33, for deflecting one 60 or more of the upper form-strips upward and out of the machine during the feeding opera- tion, while at least one of the duplicate form- strips is fed into the record-compartment, ac- cording to the disposal to be made of the used 65 forms, as for instance one copy to go to the cus- tomer, and another copy to the shipping-room, both of these forms being projected out of the machine and to be severed from their strips by tearing them on a knife edge 32a provided for 70 that purpose on the housing 32 which forms a part of the margin frame 27. Other copies of the filled-in forms may be fed into the record- compartment, without however being severed from the strips, as at F, so as to preserve a 75

seriatim record of the transactions registered by the machine.

From the foregoing description it will be understood that, (referring to Fig. 4) when the 5 margin frame 27 is in its full-line position 27A, and the platen 20 has been swung-up and toward the right to the dotted line position 20C, the associated form-strips may be pulled from the pile 10 over the guide-roller 26 and such interleaved carbon sheets as may be suspended from the hooks 20b, along the platen-top to the bite between the feeding-disks 37 and their cooperative pressure-roller 33. Now, inasmuch as the superstructures 23a, 24a of the bearing-plates 23, 24 15 are fully exposed, the pressure roller may be released from its usual hold-down spring (not shown) and bodily lifted-out of its place, consequently permitting the operator to easily thread the front edges of the several strips into their 20 proper places above and below the deflector plate 40 respectively, whereupon the pressure roller may be replaced and the platen 20 and margin frame 27 may be dropped back into their normal positions shown in Fig. 2, bringing the machine 25 into condition for practical use, with the exception of one feature, viz: that of safe-guarding the record strips within the record-compartment 18, and simultaneously the pile in the storage compartment.

30 The invention, therefore, provides for the record-compartment a cover-plate 42 hinged at 43 to the front wall 11 of the register-casing, and of such length that, when said cover is closed, its rear edge will overlap the knife edge 32a (see 35 Figs. 1 and 2) which constitutes a part of the margin-frame housing 32, this overlapping portion, however, being cut-away to provide a passage 44 for the form-strips which are moved over the deflector-plate 40 by the feed mechanism M.

40 It is sometimes necessary to raise the pressure roller 33 to release the grip between it and the feeding disk, and thus permit adjustment of the consolidated form-strips either transversely or longitudinally of the machine, and my invention 45 comprises, as one of its features, a raising device which is at all times fully enclosed in the casing and therefore inaccessible when the covers of the latter are closed. In the preferred form thereof shown, this device consists of a bar 50 50 (see Figs. 2, 3, 4) extending across the machine but located between the side-walls thereof and bent at both of its ends to form a pair of side-arms 45a which are cam-shaped at their ends and eccentrically pivoted at 46 on the outer 55 sides of the partition plates 23, 24, the construction being such that, when the bar 45 is in its normally depressed position shown in Fig. 2, the pressure-roller 33 is cooperative with the feed disks 38 in pinching the associated strips between them, and the bar is located entirely within 60 the casing. On the other hand, when the bar 45 is raised, as by a finger piece 45b, to approximately the position shown in Fig. 4, in which the pressure roller is in non-operative condition, 65 the bar assumes a position above the upper edge of the casing walls, so that, when the compartment cover 42 is being closed, it will strike the bar 45 downwardly and thus automatically re-establish cooperative relation between the feed disk and pressure roller, a condition which cannot be altered, as long as the cover 42 remains closed. In other words: when the cover 42 is up, the bar 45 may be raised or lowered at will; 70 while, when cover 42 is closed, the bar 45 can only be in its depressed position.

As above mentioned, one object of the invention is: to organize the covers of the compartments in such a manner, that their closing movements must be effected in a certain sequence and so that the cover which is closed as the final one 5 in the series, and then locked, will prevent the opening movement of any one of the other closure-elements. There exists, in fact, a definite interlock of the covers which requires a certain sequence in movements to open the casing-top 10 completely, or/and reversely, a reversed sequence when closing the covers.

In the present invention, the platen 20 cannot be raised, unless the margin-frame 27 is up. Neither can the margin frame 27 be closed over 15 the platen 20 unless the latter is down. As to the cover 42 for the record-compartment, that cover must first be opened before any of the other covers can be opened, because, when this cover is normally closed, its rear edge will overlap the knife or tear-off ledge 32a of the roller housing 32, and thus estop the margin-frame 27 from being raised.

Again, the cover 42 will not close automatically 25 or cannot be closed otherwise unless all the others are closed, particular attention being now called to an automatic stop mechanism whereby the closing movement of the cover 42 will be stopped until the margin frame is down, this mechanism becoming effective immediately upon 30 the rise of the cover 42 sufficient to permit free upward of the margin frame 27 as follows:

Pivoted at 50a to the inner face of the front portion of the casing side 14 is a stop lever 50 having a lower weighted end 50b which carries a pin 51 adapted to ride in a slot 52 provided for it in an actuator 53 which is pivoted at 53a, also on said casing-side 14, and preferably also weighted, as at 53b, to assist both levers in assuming the full-line positions in Fig. 4. There, 40 it will be noted, the margin frame is shown by dot-and-dash lines 27c in a partly raised position, at any rate sufficient to allow the upper tail-end 53c of the actuator 53 to swing upward to its maximum height as limited by the lever-pin 51 engaging the lower end of the actuator slot 52. At that time, the upper tail 50c of the lever 50 projects upwardly and above the upper casing-edge, also to its maximum height, as depending upon the pin-and-slot connection just 50 described, this height being such that the cover 42 can drop only to the position indicated by dot-and-dash lines 42A, and therefore clears the closing-swing of the margin frame 27.

Assuming that the record-compartment cover 55 42 is in its position 42A, stopped by the lever 50 and the margin-frame 27 is swung down, the housing ledge 32a will strike the upper end of the actuator-tail 53c and swing it downwardly, thus also moving the lever tail 50c downwardly 60 and permitting the cover 42 to drop over the ledge 32a, to the position shown in Fig. 1, in which position the cover 42 may be locked, as for instance by a lock L, whose lock-arm 54 is adapted to contact the underside of the fixed bar 65 41 and thus prevent the cover 42 from being raised.

From the foregoing, it is evident that, by the operation of the lock in the cover 42, the register, as a whole, becomes a closed lock-box, the 70 interior of which is inaccessible, and whose only element accessible from the outside is the manually-operable crank 36 of the feed-shaft 35.

By referring to Fig. 4, the successive steps required when opening, reclosing and locking the 75

register will be readily understood, as follows:

The register-covers are normally in the positions shown in Fig. 2, the machine being safely locked by the record-cover 42 which carries the key-lock L. When it is desired to have access to any part of the casing-interior, the first step is always: to unlock the record-cover 42 and swing it upward to at least the position 42A, resulting in liberating the margin frame 27 so that it may be swung upward on its edge hinge to its position 27A, or a trifle beyond it, until the limit has been reached by its rear edge 27a abutting the outer face of the rear end wall of the casing, as 27B, where it will remain of its own accord in fully-opened position. When the rear-end of the platen 20 is now raised to the position 20B, the storage compartment becomes fully exposed, so that the form-pile contained therein may be removed, and a new one substituted therefor, and the leading ends of the assembled new form-strips may be easily threaded over the guide-roller 26, then interleaved with the required number of carbon-sheets (suspended on the hooks 20b) and pulled-down over the platen 25 which may then be dropped to its normal position shown in Fig. 2. The leading end of the form-strips may now be entered into the bite between the feed disks 38 and the pressure roller 33; or, if for any reason it should be desired to have unobstructed access to the feed mechanism, the pivot end 21a of the platen may be swung over, in the arc 21a', to put the front edge of the platen out of the way, as per position 20C, and the record-cover 42 should be raised to its full line position of Fig. 4, leaving free access to the feed mechanism and permitting easy removal and/or replacement of any parts thereof.

Supposing that the record-strips contained in the compartment 18 are to be removed, it will

only be necessary to unlock and raise the cover 42 to its full line position of Fig. 4, lift the strips out and tear them off in proper place, and then reclose and relock not only the cover, but incidentally the platen and its superposed margin frame against opening movement.

Of course, it should be remembered that, unless the margin frame is down to its limit, the stop lever organization 50, 53 for preventing the cover 42 from prematurely going to normal, will remain in its active position shown in Fig. 4.

In brief: The cover 42 cannot be closed and locked until the other closures are in proper operative position, and when closed and locked, those closures cannot be raised, making the entire cover organization interlocked and consequently safe, by locking only one member thereof.

In the present exemplification of the invention, the register is what is generally known as a one-revolution machine, that is to say: one revolution of the feed shaft will cause the feed-disk to advance the form-strips for an amount equal to one form-length which, however, must not be greater than the circumference of the feed disks. In order to arrest the crank at the end of each revolution, there is provided on the outside of the casing-side 13 a stop illustrated in Figs. 5 to 8 inclusive.

Secured to the side wall 13, in vertical alignment with and below the crank-shaft 35, is a block 60 provided with an attachment-flange 61 which may be secured to said side wall 13 in any suitable or convenient manner. This block slidably supports a pair of plungers 62, 63 which are movable horizontally in the block 75 in opposite directions, and which have pins 62a,

63a, respectively, passing through slots provided for them in the block 60 and projecting upwardly therefrom into engagement with the ends of a lever 64 which is centrally fulcrumed on a stud 65 held in the block. A coil-spring 66 on the stud urges the lever 64 to project the plunger 62 outwardly, and simultaneously move the plunger 63 rearwardly, to the positions shown in Figs. 6 and 7, so that when the crank 36 is manually rotated from its normal position shown in Figs. 5 and 6 to that illustrated in Fig. 7, and by dot-and-dash lines in Fig. 5, the edge of the crank-arm 36 will strike against the projecting end of the plunger 62. The outer end-face of this plunger is, however, beveled, as 15 at 62b, so that, when the arm has reached the position of Fig. 7, and its movement in the direction of the arrow is continued, the plunger 62 will be cammed inwardly, this movement resulting in pushing the companion plunger 63 20 outwardly, by virtue of the rocking movement of the lever 64. In other words: the first plunger 62 is used merely to project the second plunger 63 outwardly (as the crank arm 36 passes the beveled end 62b) against the action of the spring 25 66, and directly into the path of the crank arm 36, whose movement will therefore be positively stopped by the then projecting end of the plunger 63, there being a considerable impact due to the rapidity of the crank-movement under hand-pressure, whose force is in the direction of the three arrows in Fig. 8 and sufficient to hold the plunger 63 against being returned to normal or retracted position by the spring 66. 30

Now, inasmuch as the width of the crank-arm 35 36 is less than the space between the two plungers 62, 63, the latter will be free to be returned to normal by the spring 66, as soon as the hand pressure on the crank-arm 36 is removed by the withdrawal of the operator's hand from the 40 crank which action will leave the crank in normal position ready for the next feeding operation.

Variations and modifications may be made within the scope of this invention and portions 45 of the improvements may be used without others.

I claim:

1. A manifolding register comprising a casing having in its interior a plurality of compartments; independent covers for closing said compartments, respectively, and hinged for vertical swinging movement on said casing, the free end of one of said covers overlapping, when closed, the free end of the other cover; a locking device carried by the overlapping cover for holding the latter against opening movement; and means for preventing said overlapping cover from being closed before the other cover is in its closed position.

2. A manifolding register comprising a casing 60 having in its interior a plurality of compartments; independent covers for closing said compartments, respectively, and hinged for vertical swinging movement on said casing, the free end of one of said covers overlapping, when closed, 65 the free end of the other cover; a locking device carried by the overlapping cover for holding the latter against opening movement; and a lever for stopping said overlapping cover from closing, and operable by the full-closing movement of 70 the other cover to withdraw said lever from its operative position.

3. A manifolding register comprising a casing having in its interior a plurality of compartments; independent covers for closing said com- 75

- parts, respectively, and hinged for vertical swinging movement on said casing, the free end of one of said covers overlapping when closed the free end of the other cover; a locking device carried by the overlapping cover for holding the latter against opening movement; a lever for stopping said overlapping cover from closing, and operable by the full-closing movement of the other cover to withdraw said lever from its operative position; and an actuator operated by the closing movement of the other cover to withdraw the stop lever from active position.
5. A manifolding register comprising a casing having in its interior a plurality of compartments; independent covers for closing said compartments, respectively, and hinged for vertical swinging movement on said casing, the free end of one of said covers overlapping, when closed, the free end of the other cover; a locking device carried by the overlapping cover for holding the latter against opening movement; a lever for stopping said overlapping cover from closing, and operable by the full-closing movement of the other cover to withdraw said lever from its operative position; and an actuator operated by the closing movement of the other cover to withdraw the stop lever from active position.
4. A manifolding register comprising a casing having in its interior a plurality of compartments; independent covers for closing said compartments, respectively, and hinged for vertical swinging movement on said casing, the free end of one of said covers overlapping, when closed, the free end of the other cover; a locking device
- 10
- 15
- 20

carried by the overlapping cover for holding the latter against opening movement; a lever for stopping said overlapping cover from closing, and operable by the full closing movement of the other cover to withdraw said lever from its operative position; and an actuator operated by the closing movement of the other cover to withdraw the stop lever from active position.

5. A manifolding register comprising a casing having in its interior a plurality of compartments; strip-feeding means disposed within the casing between the compartments, the feeding means having separable rollers; means for separating the rollers whereby the strips can be positioned therebetween; and means for covering the compartments, said means cooperating with the means for separating the rollers to return the rollers into gripping relation with the strips when the covers are closed.

WILLIAM G. BORCHERS. 20
